UNITED STATES PATENT OFFICE

EDSON C. BAUGHMAN, OF KANSAS CITY, MISSOURI

DESIGN FOR A COMBINATION FOOT WARMER AND STOOL

Application filed June 16, 1930. Serial No. 36,070. Term of patent 14 years.

To all whom it may concern:

Be it known that I, EDSON C. BAUGHMAN, a citizen of the United States, residing at Kansas City, county of Jackson, State of Missouri, have invented a new, original, and ornamental Design for Combination Foot Warmer and Stool, of which the following is a specification, reference being had to the accompanying drawing, forming a part thereof.

The drawing represents a perspective view of a combination foot warmer and stool, showing my new design.

I claim:

The ornamental design for a combination foot warmer and stool, as shown.

EDSON C. BAUGHMAN.
